UNITED STATES PATENT OFFICE.

THOMAS WEBSTER, OF NEW YORK, N. Y.

METHOD OF BACKING ELECTROTYPE.

1,202,933.

Specification of Letters Patent. Patented Oct. 31, 1916.

Original application filed June 24, 1915, Serial No. 36,148. Divided and this application filed January 19, 1916. Serial No. 72,917.

To all whom it may concern:

Be it known that I, THOMAS WEBSTER, a citizen of the United States of America, and a resident of New York, in the borough of Brooklyn, county of Kings, and State of New York, have invented certain new and useful Improvements in Methods of Backing Electrotypes, whereof the following is a specification.

10 In the methods of backing electrotypes as heretofore practised, the shell forming the body of the electrotype after removal from the electrolytic bath is cleaned and placed face downward on a backing pan which has 15 a very smooth surface. Then a liquid backing metal is poured over the shell in the pan to a depth required for the thickness of the backing desired. Then the pan and its contents are subjected to a cooling operation 20 which solidifies the molten metal around the shell and forms the backing therefor. This cooling operation usually consists in exposing the pan and its contents to an ordinary temperature for a sufficient time of say from 25 twenty-five minutes to half an hour, or in subjecting the pan and its contents to a blast of air from a blower whereby the time of cooling is reduced to say five minutes more or less. But in both these methods of cooling 30 the metal of the backing shrinks more or less unequally from the pan and causes irregularities on the printing surface of the electrotype plate, which irregularities must be corrected by a finishing operation before 35 the plate can be delivered in a condition acceptable to the user. This finishing is an expensive and time consuming step.

The objects of this invention are to shorten the cooling step and to perform it 40 in such manner as to avoid the inequalities referred to and do away with the leveling operation usually required after the cooling operation is completed.

In carrying out this invention in its preferred form, the pan containing the shell and the backing material covering it, is subjected to chilling material applied to the bottom thereof, preferably in the form of an absorbent pad saturated with water. This 45 effects a sudden chilling of the bottom of the pan and the cold passes by conduction therethrough and touches the shell and the backing material surrounding it on the lower face thereof and causes all parts of the case 50 to shrink toward the pan, and the weight

of the hot molten metal above the shell serves to press the face of the latter against the pan. Under this cooling operation an electrotype is produced quickly and without inequalities on its printing face.

60 In the accompanying drawings, which illustrate a convenient apparatus for carrying out this process, Figure 1 represents a side elevation partly in section of a backing pan and cooling pan, the former containing the shell and backing material and the latter containing the cooling pad in position preparatory to effecting the cooling operation. Fig. 2 represents a longitudinal section of the pans in operative position for 65 cooling, the cooling pad being in contact with the bottom of the backing pan. Fig. 3 represents a modified form of the apparatus in which the cooling material consists of the water in the cooling pan, the pad being 70 omitted.

75 Similar reference numbers indicate corresponding parts in the different figures.

The method may be carried out by an apparatus comprising a backing pan 10 for 80 containing the electrolytic shell and the backing material, a cooling pan 20 for containing the cooling material and means for shifting one of said pans to place the bottom 85 of the backing pan in contact with the cooling material in the cooling pan. The backing pan 10 is supported by suspension rods 11 or otherwise and has the upper face of its bottom smoothed in the usual manner and the underface thereof exposed for contact 90 with the cooling material in the cooling pan.

95 The cooling pan 20, which carries cooling material for contact with the bottom of the backing pan 10, is provided with an inlet 5 nipple 21 and an outlet nipple 22. A flexible water supply pipe 23 connects with the nipple 21, and a flexible exhaust pipe 24 connects with the nipple 22. An absorbent pad 25 preferably composed of felt is disposed in the cooling pan. Water flows in through the inlet 21 and through the outlet nipple 22 and a current may be maintained through 100 the pan and the pad mounted therein.

105 One of the pans is moved by any suitable means to cause the cooling material in the cooling pan to contact with the backing pan. The means shown includes a rock shaft 30, arms 31 and 32 fixed thereto, lifting levers 33 and 34 engaging the cooling pan, links 35 and 36 connecting said arms with said 110

levers and an actuating lever 37 attached to said shaft.

In carrying out by means of this apparatus the cooling step in the backing method, 5 the shell 40 of the electrotype is placed with its printing face downward in contact with the upper face of the bottom of the backing pan 10 and the usual molten metal 45 is poured into said pan, covering said shell, 10 and the weight of said metal over the shell presses the latter down against the bottom of the pan. The cooling pan 20 is then lifted by the lifting mechanism referred to until the top of the cooling pad 25 comes in 15 contact with the exterior of the bottom of the backing pan 10. Heat is interchanged by conduction through the bottom of the backing pan between the hot molten metal therein and the cooling water contained in 20 the absorbent pad 25. The hot backing pan coming in contact with the wet cooling pad causes more or less evaporation or vaporization of the water, which increases the cooling effect. Water is supplied through the 25 inlet to take the place of that evaporated. The quantity of water maintained in the cooling pan is such that the pad is thoroughly saturated therewith, but the water does not form a layer above the surface of 30 the pad under normal conditions.

The pad 25 may be omitted if desired as shown in Fig. 3. In that case the water or other evaporative liquid supplied to the cooling box comes bodily into contact with the 35 bottom of the backing pan containing the shell and backing metal to be cooled; but I find it preferable in practice to bring the evaporative liquid into contact with the bottom of the backing pan through the capillary action of the pad. This is probably 40 due to the fact that the pad distributes the evaporative liquid to the bottom of the backing pan through capillary action and permits the passage of air between the fibers of 45 the pad and increases the evaporation of the liquid and thereby intensifies the cooling effect.

The advantages of this method of cooling by water contact and evaporation are that 50 the sudden chilling by conduction through the bottom of the backing pan of the face of the casting causes the metal as it cools to shrink toward and into contact with the upper face of the backing pan, the plates being 55 all shrunk alike and the faces thereof drawn down flat, doing away with straightening in many cases, especially on type and half-tones, providing the backing pan is smooth

and clean. Moreover, the heat units of the casting being readily absorbed by the continuously moistened felt pad, the casts are cooled off in forty seconds. Thus the capacity of a plant is enlarged and at the same time the product is improved and the expense of a blower is eliminated.

This case is a division of my apparatus application Serial No. 36,148 filed June 24, 1915.

I claim as my invention:

1. The method of backing electrotypes 70 which consists in placing the solid shell face downward in contact with the upper face of the metallic bottom of a backing pan, pouring molten backing metal in said pan to a depth which covers said shell, and subjecting at once the whole area of the bottom of said pan while said solid and liquid metals are in touch therewith to uniform contact with an evaporative cooling liquid.

2. The method of backing electrotypes 80 which consists in placing the shell face downward in contact with the upper face of the metallic bottom of a backing pan, pouring molten backing metal in said pan to a depth which covers said shell, and subjecting 85 the bottom of said pan to contact with an absorbent pad containing an evaporative cooling liquid.

3. The method of backing electrotypes 90 which consists in placing the shell face downward in contact with the upper face of the metallic bottom of a backing pan, pouring molten backing metal in said pan to a depth which covers said shell, and subjecting 95 the bottom of said pan to contact with an absorbent pad composed of felt and containing an evaporative cooling liquid.

4. That step in the art of backing electrotypes which consists in subjecting the bottom of a backing pan containing the solid shell and the molten backing metal while both touch said bottom to uniform contact over its whole area with a cooling evaporative liquid, whereby the face of the electrotype only is subjected to a chilling operation 100 causing the metal to shrink toward the pan and avoiding irregularities on the face of the electrotype.

In testimony that I claim the foregoing as my invention, I have signed my name in 110 presence of two subscribing witnesses.

THOMAS WEBSTER.
